UNITED STATES PATENT OFFICE.

VICTOR NIVOIS, OF BROOKLYN, NEW YORK.

CIGARETTE-CASE.

1,232,072.

Specification of Letters Patent.

Patented July 3, 1917.

Application filed December 9, 1914. Serial No. 876,275.

To all whom it may concern:

Be it known that I, VICTOR NIVOIS, a citizen of France, residing at Brooklyn, in the county of Kings and State of New York, have invented new and useful Improvements in Cigarette-Cases, of which the following is a specification.

This invention relates to cases such as used for carrying articles and which are opened from time to time to remove the articles.

While the invention is applicable to cases for carrying articles of many kinds, I have described it in the accompanying specification as applied to a case for cigars, cigarettes or similar articles.

My invention relates particularly to the type of case of this kind which comprises two connected case sections which are adapted to swing apart in opening the case and which, when the case is open, display a holder carrying the cigarettes in an upright position in the angle or space between the two case sections. When the case is closed, the holder folds into the space between the case sections.

A principal object of the invention is to produce a case of this general type having a very simple and neat construction and having very simple means for enabling the case to operate in the manner stated above.

A further object of the invention is to improve also the construction of the holder for the cigarettes and to produce a holder of very simple construction and of neat appearance.

A further object of the invention is to produce a holder which though especially adapted for use in a case of the type described will have features which may be used without the case and particularly relating to the means for attaching the walls of the holder, enabling the same to be moved away from each other to facilitate the filling of the holder, but operating to return either of the walls of the holder after being moved away from its normal position.

Further objects of the invention will appear more clearly hereinafter.

The invention consists in the general combination of parts and features hereinafter

described, all of which contribute to produce an efficient case and an efficient holder.

A preferred embodiment of my invention will be particularly described in the following specification, while the broad scope of my invention will be pointed out in the appended claims.

In the drawings:—

Figure 1 is a perspective of a case embodying my invention.

Fig. 2 is a front elevation of one of the case sections of the cigarette holder showing its inner face and showing the other case section as viewed in cross section near the hinge connection between the case sections.

Fig. 3 is a side elevation showing the adjacent ends of the case sections slightly apart and indicating the manner in which they are alined with each other when being connected together.

Fig. 4 is a cross section upon an enlarged scale taken through the hinge connection of the case, showing the same in an open position, and also showing the inner portion of the holder.

Fig. 5 is a section at the inner portion of the holder, taken longitudinally through the axis on which the side plates of the holder are attached to the central plate. This view particularly illustrates the manner in which the hinge connection is formed at this point, and the very simple means for permitting either of the side plates to swing away from each other or the central plate, and for returning them when so moved.

Fig. 6 is a plan view of the three members of the cigarette holder, the members being detached from one another.

Referring more particularly to the parts, 10 and 11 represent two case sections consisting of two shallow dished plates which are normally closed together to form a case which may be conveniently carried in one's pocket.

These case sections are joined together preferably by means of a hinge connection including a pintle 12. In order to form this hinge connection, I prefer to produce sleeves 13 on one of the case sections, (see Fig. 3) and adjacent alining sleeves 14 on the other case section. These sleeves are ar-

ranged so that when the two case sections are brought together to form the hinge, they will aline with each other end to end, as illustrated in Fig. 2. Through these alining sleeves the pintle 12 passes.

The sleeves 13 and 14 are near the ends of the hinge connection. Near the middle of the connection I provide a special sleeve 13^a on the case section 11, and a similar special sleeve 14^a on the case section 10. These sleeves 13^a and 14^a are adapted to aline with each other and receive the pintle in the same manner with the other sleeves, but they have an additional function which will presently appear. In order to enable these sleeves to perform this additional function I prefer to provide the sleeve 13^a with an outwardly projecting part or finger 13^b and a similar projecting finger or part 14^b is formed on the opposite sleeve. The relation of these projecting parts or fingers is clearly illustrated in Fig. 4, from which it is evident that the part 13^b though carried by or formed on the case section 11, is on the opposite side of the axis of the pintle 12; similarly, the part 14^b which is carried by the case section 10, is on the opposite side of the axis of the pintle 12 from the case section 10. In other words, each of these parts is beyond the hinge connection with respect to the case section with which it moves.

From this arrangement it will be evident that when the case sections are swung apart to open the case, these parts 13^b and 14^b will approach each other. However, between them lies a part 15 of the cigarette holder 16 which is in their path and engaged by them preferably in the manner indicated in Fig. 4, so that when the case sections are open the holder will be held in an upright position between the case sections.

In order to get this effect, I prefer to construct the holder 16 with a central plate 17, arranged so that the part 15 forms the lower edge of this plate, and is disposed between two sleeves 18, which sleeves are alined with the sleeves 13 and 14 at the time the pintle 12 is placed in position; so that the pintle also attaches the holder at the hinge connection. These sleeves 18 fit neatly in the space between the sleeves 13^a and 14, and between the sleeves 13 and 14^a respectively, so that there is no longitudinal play for the holder or for the case sections after being connected by the pintle. The pintle 12 performs the function of normally tending to swing the case sections apart when closed, but the case sections are normally prevented from opening by a catch 19 of any suitable construction.

In order to get this effect, one end of the pintle is rigidly attached to a sleeve such as the sleeve 13 at the left side of Fig. 3 and the other end of the pintle is rigidly at-

tached to the sleeve 14 at the other side, that is at the right side of the figure, and on the opposite case section, and the pintle is placed in torsion before being secured to these sleeves so that it constantly tends to swing the case sections apart.

It is evident that when the case is being closed the part 13^b will approach the dished body portion of the case-section 10. In order to provide clearance, to permit this I prefer to cut a gap or notch 25 in the case section 10 adjacent this point. A similar gap 26 is formed in the other case-section 11 to allow for the movement of the part 14^b.

The holder 16 preferably comprises side plates 20 which are hinge connected with the inner or lower part of the central plate 17. In order to effect this connection, I prefer to form the lower portion of the central plate 17 with an elongated sleeve 21, and each of the side plates 20 is preferably formed with two sleeves, namely, a sleeve 22 at one end and a sleeve 23 at the other end. These sleeves are alined with each other and are oppositely arranged so that the sleeve 22 of each side plate comes against one end of the sleeve 21.

In the sleeve 21 there is preferably placed loosely a resilient pintle or spring 24 which preferably consists of two or more elongated strips of steel twisted together preferably in the manner indicated in Fig. 5. This pintle, while being put in position, is held twisted, and while in a state of torsion the sleeves 23 through which it passes are rigidly secured to it. The torsional force in the spring 24 exerted thereafter tends to rotate the side walls 20 toward the center plate 17 and hence, if either of the walls 20 is swung away from the central plate 17 it will be returned by the spring when released. The side plates 20 are preferably of corrugated form so as to hold a single row of cigarettes neatly between the side plate and the center plate 17, and the upper edge of the center plate preferably projects above the upper edges of the side plates so as to facilitate the filling of the holder.

After the member 24 is in place, the ends of the outer sleeves may be closed by plugs 27.

It is understood that the embodiment of my invention as described above is only one of the many embodiments or forms the invention may take, and I do not wish to be limited in the practice of my invention, nor in my claims, to the particular embodiment set forth.

What I claim is:—

1. A case for cigarettes comprising two case sections having a hinge connection therebetween, arranged to swing apart in opening the case, each of said case sections having an outwardly projecting part beyond

the axis of the hinge connection wholly within the case, whereby said parts approach alinement with each other when the case sections are moved to their open position, 5 and a holder for the cigarettes attached at said hinge connection and having a part lying between and in the path of said first named parts to engage the same and thus maintain said holder in an upright position 10 when said case sections are opened to their limit.

2. A case for cigarettes comprising two case sections having a hinge connection therebetween, arranged to swing apart in 15 opening the case, each of said case sections having an outwardly projecting part beyond the axis of the hinge connection wholly within the case, whereby said parts approach alinement with each other when the case 20 sections are moved to their open position, and a holder for the cigarettes attached at said hinge connection and having a part extending longitudinally along the edge of said holder adjacent the hinge and lying 25 between and in the path of said first named parts to engage the same and thus maintain said holder in an upright position when said case sections are opened to their limit.

3. A case for cigarettes comprising two case 30 sections having a hinge connection including a pintle therebetween, arranged to swing apart in opening the case, each of said case sections having a sleeve rigid therewith, loose on the said pintle and having an outwardly projecting part beyond the axis of the hinge connection wholly within the case, whereby said parts approach alinement with each other when the case sections are moved to their open position, and a holder for the 35 cigarettes attached to the pintle at said hinge connection and having a part lying between and in the path of said first named parts to engage the same and thus maintain said holder in an upright position when said 40 case sections are opened to their limit.

4. A case for cigarettes comprising two case sections having a hinge connection therebetween, arranged to swing apart in opening the case, a holder for the cigarettes 50 attached at said hinge connection, having two hingedly supported side walls to retain the cigarettes and adapted to swing away from each other, and a resilient pintle member constantly under torsion operating to 55 return either of said side walls when swung away from the other.

5. A holder for cigarettes comprising a central dividing plate, a pair of side walls attached to said central plate so as to swing 60 away from the same, and a torsional spring pintle supported in said central plate and connected with both of said side walls and operating to return either of said side walls when swung away from said central plate.

6. A case for cigarettes comprising two case 65 sections having alining sleeves, a hinge pintle passing through said alining sleeves, each of said case sections having an outwardly projecting part adjacent one of its sleeves and beyond the axis of said pintle and lying 70 wholly within the case, whereby said parts approach alinement with each other when the case sections are moved to their open position, and a holder plate attached to said pintle and having a part lying between and 75 in the path of said first named parts to engage the same and thus maintain said holder plate in an upright position when said case sections are opened to their limit, said plate having a sleeve near the inner end thereof, 80 side walls on opposite sides of said plate, one of said side walls having a rigid sleeve at one end of and alining with the said sleeve of said plate, the other of said side walls having a rigid and alining sleeve at the 85 other end of said sleeve of said plate, and a torsional spring lying in the sleeves of said side walls normally holding said side walls against said plate, and operating to return either of said side walls when moved away 90 from said plate, said side walls coöperating with said holder plate to hold cigarettes therebetween.

7. A cigarette case comprising two case 95 sections, a hinge connection for said case sections including a hinge pintle constantly under torsion, and a cigarette holder located within and adapted to be inclosed by the case sections, said holder including two wall members and means, including a hinge pintle under constant torsion, for hingedly connecting said wall members.

8. A case for cigarettes comprising two case sections having a hinge connection therebetween, arranged to swing apart in 105 opening the case, each of said case sections having an outwardly projecting part beyond the axis of the hinge connection wholly within the case, whereby said parts approach alinement with each other when the case 110 sections are moved to their open position, a holder for the cigarettes attached to said hinge connection and having means lying in the path of said first named parts to engage the same and thus maintain said holder in an upright position when said case sections are open to their limit.

9. A case for cigarettes comprising two case sections having a hinge connection therebetween, arranged to swing apart in 120 opening the case, each of said case sections having an outwardly projecting part beyond the axis of the hinge connection wholly within the case, whereby said parts approach alinement with each other when the case 125 sections are moved to their open position, and a holder for the cigarettes attached at said connection having means extending

longitudinally along the edge of said holder adjacent the hinge and lying in the path of said first named parts to engage the same and thus maintain said holder in an upright 5 position when said case sections are open to their limit.

In testimony whereof I have hereunto set

my hand in presence of two subscribing witnesses.

VICTOR NIVOIS.
